(57) **CLAIM**

The ornamental design for an eyeglass protective case, as shown.

DESCRIPTION

FIG. 1 is a perspective view of an eyeglass protective case according to the present application.

FIG. 2 is a front view of the eyeglass protective case of FIG. 1.

FIG. 3 is a back view of the eyeglass protective case of FIG. 1.

FIG. 4 is a left view of the eyeglass protective case of FIG. 1.

FIG. 5 is a right view of the eyeglass protective case of FIG. 1.

FIG. 6 is a top view of the eyeglass protective case of FIG. 1; and,

FIG. 7 is a bottom view of the eyeglass protective case of FIG. 1.

The broken lines are included for the purpose of illustrating environmental structure and form no part of the claimed design.
